UNITED STATES PATENT OFFICE

2,472,276

PROCESS FOR THE PRODUCTION OF ARYL-
DESOXYGLYCOSES AND DIARYLDESOXY-
ALDITOLS

William Andrew Bonner, Hubbard Woods, and Charles D. Hurd, Evanston, Ill., assignors to Corn Products Refining Company, New York, N. Y., a corporation of New Jersey

No Drawing. Application December 31, 1945,
Serial No. 638,583

8 Claims. (Cl. 260—333)

1

This invention relates to the production of new classes of organic chemical compounds and more particularly to a process for the production of aryldesoxyglycoses and diaryldesoxyalditols and derivatives thereof. The object of the present invention is to provide a process for the production of such compounds.

The first of the new classes of compounds, i. e., aryldesoxyglycoses, obtained by the process of the present invention may be represented by the following general formula wherein Ar represents an aryl radical and n, a whole number, usually 3 or 4:

A specific example of an aryldesoxyglycoses obtained by the process of the present invention is D-glucopyranosylbenzene. Two alternate names for this compound are 1-phenyl-1-desoxy-D-glucose and 1-phenyl-1,6-anhydro-D-glucitol. The structural formula for this compound may be represented as follows:

A specific example of a derivative of an aryldesoxyglycoses obtained by the process of the present invention is tetraacetyl-D-glucopyranosylbenzene. An alternate name for this compound is 1-phenyl-1-desoxy-2,3,4,6-tetraacetyl-D-glucose. It may be represented by the following structural formula:

2

derivatives obtained by the process of the present invention include

D-xylopyranosylbenzene (or 1-phenyl-1-desoxy-D-xylose)

5 Triacetyl-D-xylopyranosylbenzene

D-galactopyranosylbenzene (or 1-phenyl-1-desoxy-D-galactose)

Tetraacetyl-D-galactopyranosylbenzene

10 p-D-glucopyranosyltoluene (or 1-tolyl-1-desoxy-D-glucose)

p(Tetraacetyl-D-glucopyranosyl)toluene

The second of the new classes of compounds, i. e., diaryldesoxyalditols, obtained by the process 15 of the present invention may be represented by the following general formula wherein Ar and Ar' represent aryl radicals, and n is a whole number, usually 3 or 4.

20

A specific example of a diaryldesoxyalditol is 1,1-diphenyl-1-desoxy-D-glucitol. This may be 25 represented by the following structural formula:

30

35

A specific example of a derivative of a diaryl-35 desoxyalditol is 1,1-diphenyl-1-desoxy-2,3,4,5,6-pentaacetyl-D-glucitol. This may be represented by the following structural formula:

40

45

Further examples of diaryldesoxyalditols include

50 1,1-di-p-tolyl-1-desoxy-D-glucitol

1,1-diphenyl-1-desoxy-D-galactitol

1,1-diphenyl-1-desoxy-D-xylitol

The above aryldesoxyglycoses and diaryldesoxyalditols may be produced according to the present invention by bringing about the reaction

between a carbohydrate derivative possessing certain hereinafter specified characteristics and an aromatic hydrocarbon or specific substitution product thereof in the presence of anhydrous aluminum chloride.

The above reaction will be recognized as involving an adaptation of the Friedel-Crafts reaction. While the Friedel-Crafts reaction is well known, it is surprising that it has never been applied to carbohydrate derivatives and aromatic hydrocarbons to produce aryldesoxyglycoses and diaryldesoxyalditols.

The reaction of the present invention is believed to proceed according to the following illustrative equation, involving the use, in this instance, of an aldohexose derivative as one of the reactants,

wherein Ar represents an aryl group; Y represents chlorine, bromine, or an acyloxy group; and R represents an alkyl group. The $>\text{CHOH}$ groups represented in the above formulae actually do not appear until water has been added to isolate the desired products, as will be described later. They are probably held by the aluminum chloride in the following manner— $>\text{CHOAlCl}_2$. The diaryldesoxyalditols are actually formed by the reaction of aryldesoxyglycose with aromatic hydrocarbon in the presence of aluminum chloride.

In carrying out the present invention there may be used as one of the reactants any carbohydrate derivative containing an aldehydic or ketonic function, the carbon atom of which has attached to it a group Y; Y, as already mentioned, may be chlorine, bromine or an acyloxy group. The term carbohydrate derivative as used herein and in the appended claims is intended to refer to a compound obtained from the carbohydrate, wherein the skeleton of the carbohydrate (i. e., the carbon chain) remains substantially intact. The term derivative is thus to be distinguished from a modification in which the original carbohydrate skeleton may be degraded or increased or otherwise changed. The term acyloxy as used herein and in the appended claims is intended to refer to an acyl group holding an oxygen. In general, any aldose or ketose in which the carbon atom of the aldehydic or ketonic function has attached to it a group Y as above defined is satisfactory. Polyacylglycosyl halides or acetates are generally suitable. Examples of carbohydrate derivatives which may be employed in the process of our invention include the alpha or beta forms of glucose pentaacetate, xylose tetraacetate, fructose pentaacetate, arabinose tetraacetate, galactose pentaacetate, mannose pentapropionate. The halogen derivatives of carbohydrates which may be used in the process of this invention include tetraacetylglucosyl chloride, tripropionylarabinosyl bromide and tetraacetylfructosyl chloride.

In carrying out the invention both substituted

and unsubstituted aromatic hydrocarbons may be used. Among the aromatic hydrocarbons which may be used in the process of the present invention are benzene, toluene, xylene, naphthalene. Compounds such as bromobenzene, anisole, thiophene and the like may be used also. In fact any of the type of substituted or unsubstituted aromatic hydrocarbons which are known to undergo the Friedel-Crafts reaction in general may also be used here. As the term hydrocarbon is used herein in the description and claims, it is intended to refer to both substituted and unsubstituted hydrocarbons.

The amount of aluminum chloride which is used as a catalyst in the process of the present invention is an important factor. In order to effect the reaction between carbohydrate derivatives and aromatic hydrocarbons in accordance with the present invention, it is necessary to use at least about $x+1$ molecular equivalents of aluminum chloride, with respect to the amount of carbohydrate derivative where x equals the number of substituents, such as acyl and the like, on the carbon atoms other than the aldehydic or ketonic function. Considerably larger amounts of aluminum chloride may be used also, although there is no advantage in using more than about 6 to 8 molecular equivalents of aluminum chloride for a pentose derivative, 8 to 10 for a hexose derivative, or 10 to 12 for a heptose derivative.

The amount of aluminum chloride used as catalyst in the reaction between the above specified carbohydrate derivatives and aromatic hydrocarbons determines the relative proportions of aryldesoxyglycoses and diaryldesoxyalditols, respectively, which are formed. As already mentioned, aryldesoxyglycoses react with aromatic hydrocarbons in the presence of aluminum chloride to form diaryldesoxyalditols. If the minimal amount of aluminum chloride is used, a relatively large amount of aryldesoxyglycose will be formed while the amount of diaryldesoxyalditol will be relatively small. If, however, larger amounts of aluminum chloride, e. g., about 8 to 10 molecular equivalents for a hexose derivative, are used, then the diaryldesoxyalditol will be formed in much larger quantities than the aryldesoxyglycose, i. e., the diaryldesoxyalditol becomes the primary product.

In carrying out the process of the present invention, the carbohydrate derivative reactant is mixed with an excess of an aromatic hydrocarbon and to this mixture is added anhydrous aluminum chloride. This mixture is heated with stirring until the reaction is complete. Hydrogen chloride gas is evolved copiously at first but subsides as the reaction continues. During the reaction, the aluminum chloride changes from a powder to a light gum and eventually dissolves in the aromatic hydrocarbon which in addition to being one of the reactants also serves as the reaction medium. After the reaction is complete, the mixture is allowed to cool and is then mixed with several volumes of cold water. This treatment causes the disappearance of the $>\text{CHOAlCl}_2$ complexes and the appearance of the $>\text{CHOH}$ groups in the aryldesoxyglycose and diaryldesoxyalditol. Two layers are formed, an aqueous layer and a non-aqueous layer. These are separated in any suitable manner. Both aryldesoxyglycose and diaryldesoxyalditol are found in the aqueous layer. The catalyst, now in the form of a soluble aluminum salt, is also found in this layer. The aromatic ketone, i. e., the ArCOR in the above equation together with the excess hy-

drocarbon and higher boiling, tarry products appear in the non-aqueous layer. The ketone may be separated from the non-aqueous layer and purified by vacuum distillation or other suitable means. The excess of aromatic hydrocarbon may be recovered in similar manner.

The recovery of the desired products from the aqueous layer is effected by first adding thereto an alkaline substance, such as sodium hydroxide, in amount sufficient to adjust the pH value thereof to about 7.0. This treatment produces aluminum hydroxide which is then removed, as by filtration or the like. The water is then removed from the remaining filtrate, as by evaporation under diminished pressure. There then remains a dark colored sirup. In addition to the desired products, this sirup contains inorganic salts.

The treatment of the sirup for the recovery of aryldesoxyglycose and diaryldesoxyalditol therefrom may vary with the respective amounts of each of these two products present. In cases when the amount of catalyst used is sufficient to produce diaryldesoxyalditol in large quantity, it is usually preferable to isolate this compound first. This may be effected by first treating the sirup with a solvent for aryldesoxyglycose and diaryldesoxyalditol, such as pyridine, to obtain an extract and then removing such solvent from the extract. This step separates the desired products from the inorganic salts and is optional. After removal of the solvent a sirup again remains. The sirup whether previously treated with the solvent or not is then dissolved in only as much hot water as is necessary for this purpose and the solution allowed to cool. The diaryldesoxyalditol being considerably less soluble in water than the aryldesoxyglycose will crystallize from the solution upon cooling while the aryldesoxyglycose remains in solution. The crystals, after separation, may be recrystallized from water for further purification. The mother liquor remaining after the diaryldesoxyalditol has been removed is evaporated to dryness, leaving a colored sirup, containing the aryldesoxyglycose. As an optional step, this sirup may be treated with a suitable solvent such as 2-propanol to obtain the aryldesoxyglycose in pure form; removal of the solvent leaves the aryldesoxyglycose, either in solid form or as a sirup.

It is often desirable to recover the aryldesoxyglycose in the form of a derivative thereof, such, for example, as the acetate. This derivative may be formed by treating sirup containing or consisting of aryldesoxyglycose, according to known procedures, with acetic anhydride and sodium acetate. After the addition of water to hydrolyze the excess acetic anhydride, the acetylated product or acetate derivative of the aryldesoxyglycose may be extracted from the mixture by means of a suitable solvent such as ethyl ether. The ether extract is washed and decolorized in suitable manner and then the ether is removed therefrom. There then remains the acetate of the aryldesoxyglycose usually in solid form. This solid may be recrystallized from a suitable solvent, such as 2-propanol. If desired, the acetate of the aryldesoxyglycose may be deacetylated according to known procedures by means of sodium and methanol. After deacetylation is complete the solution remaining is evaporated to dryness, leaving the aryldesoxyglycose.

In cases when the sirup first above mentioned contains the aryldesoxyglycose in large quantity or when both products are present in isolable quantities, the sirup may advantageously be

treated, as with acetic anhydride and sodium acetate, to form acetate derivatives of both the aryldesoxyglycose and the diaryldesoxyalditol. After hydrolysis to decompose excess acetic anhydride the acetylated products may be extracted from the mixture by means of a suitable solvent, such as ethyl ether. Removal of the ether leaves a sirup containing the acetates of both the desired products. These may be separated by fractional crystallization from a suitable solvent, such as 2-propanol. Each of the acetates may then be deacetylated in the manner previously described.

The process of the present invention may be carried out in any reaction vessel which is equipped with suitable means for agitation and to allow for the escape of hydrogen chloride gas as it is evolved and also to allow the reaction mixture to be maintained at suitable reaction temperature without the loss of the reactants, particularly the aromatic hydrocarbon.

The temperature at which the reaction mixture should be heated will depend upon the ingredients therein, but in general should not exceed about 100° C. Generally, temperatures equivalent to those obtained by heating the reaction mixture on a steam bath are satisfactory.

Each of the reactants and also the catalyst should be in anhydrous form in order to carry out the reaction properly. The commercial grade of anhydrous aluminum chloride used for catalytic purposes is satisfactory for purposes of the present invention. The bulk of the catalyst should be added at the beginning if it is desired not to add all of the catalyst at one time.

The time required for the reaction to take place will depend upon the individual reactants present, but generally a period of heating, under conditions as above described, for 4 to 8 hours is satisfactory.

An excess of the aromatic hydrocarbon should be used if the hydrocarbon is intended to serve as the reaction medium. Generally, the excess should be equal to at least about 60 times the amount of the hydrocarbon actually undergoing reaction. As already mentioned, the excess hydrocarbon may be recovered. Other solvents, such as carbon disulfide, which are known to serve as reaction media for the Friedel-Crafts reaction, may also be used here for such purpose.

The carbohydrate derivative should be at least partially, if not completely soluble in the aromatic hydrocarbon with which reaction is to be effected, or in a common solvent for both reactants which may serve as a reaction medium. The introduction of substituent groups, such as acyl, alkyl and the like, on the carbon atoms other than the carbon of the aldehydic or ketonic functional group is an effective means of imparting the desired solubility characteristics to the carbohydrate derivative.

The amount of water added to decompose the aluminum complex should preferably be large enough to dissolve the desired products. In some cases the diaryldesoxyalditol may be rather insoluble in water as compared to aryldesoxyglycose which are very soluble and in order to isolate the desired compounds easily, it is preferable to have them both in the water layer.

The adjustment of the pH may be effected by a variety of alkaline substances. Sodium hydroxide, potassium hydroxide, sodium carbonate, ammonium hydroxide and the like are satisfactory for this purpose.

Other derivatives than the acetate may be used to isolate the aryldesoxyglycose. Among these

may be mentioned the propionate, butyrate, benzoate and the like. The diaryldesoxyalditol is preferably isolated as such but suitable derivatives such as the acetate, propionate, butyrate and the like may also be used.

Other solvents which may be used to purify the acetates of both aryldesoxyglycose and diaryldesoxyalditol include methanol, ethanol and similar alcohols. As previously mentioned the diaryldesoxyalditols are most easily purified by crystallization from water.

Other solvents besides ether which may be used to extract the acetates of either aryldesoxyglycose or diaryldesoxyalditol from the products of acetylation above referred to include benzene, ethyl acetate, chloroform and the like.

The following examples which are intended as informative and typical only and not in a limiting sense will further illustrate the invention, which is intended to be limited only in accordance with the scope of the appended claims.

Example 1.—Preparation of 1-phenyl-1-desoxy-2,3,4,6-tetraacetyl-D-glucose. A mixture consisting of 20 grams (0.055 mole) of 2,3,4,6-tetraacetyl-D-glucosyl chloride in anhydrous condition; 300 milliliters (3.39 moles) of benzene which had been dried over calcium chloride; and 38 g. (0.28 mole) of anhydrous aluminum chloride containing 5% of alumina was placed in a three necked flask. The flask was equipped with means for mechanical stirring, means for refluxing the mixture and for absorption of hydrogen chloride gas, and means for introducing more catalyst, if desired. The mixture was heated on a steam bath under reflux conditions and with mechanical stirring for 4 hours. Then 5 g. more of anhydrous aluminum chloride was introduced, and refluxing was continued for 3 hours more. Then the mixture was allowed to cool, and thereafter was poured into 500 ml. of cold water. The two layers formed upon addition of water were separated.

The benzene layer, after being washed with alkali solution and water, dried over sodium sulfate and filtered, was distilled. Upon fractionation of the 15.8 g. of oil which remained after removal of benzene, 11 g. of acetophenone, 3 g. of material boiling at 240–250° C. (at 110 mm. pressure) and 0.5 g. of residue were obtained.

To the water layer was added sodium hydroxide until the mixture was neutral to litmus. It was then filtered to remove aluminum hydroxide. The aluminum hydroxide cake was washed with water and the washings added to the filtrate remaining after removal of aluminum hydroxide. The water was removed from the combined filtrate and washings by distillation under diminished pressure. The residue remaining weighed about 50 g. and contained a large amount of sodium chloride. The 1-phenyl-1-desoxy-D-glucose was extracted from the residue by treatment thereof three times with 200 ml. portions of hot pyridine. After the pyridine was distilled off from the extract there remained 5.6 g. of crude 1-phenyl-1-desoxy-D-glucose in the form of a brown sirup. This was acetylated by adding thereto 40 ml. of acetic anhydride and 2 g. of sodium acetate and heating the resulting mixture with agitation for 2 hours on a steam bath. The excess of acetic anhydride was removed by adding water to the mixture, thereby hydrolyzing the acetic anhydride. The desired product above mentioned, now in acetylated form, was recovered from the mixture, after hydrolysis of the acetic anhydride, by extraction with ether. The ether extract was

washed with water, then with 4% sodium hydroxide (which removed most of the color), again with water, and finally dried over sodium sulfate. Decolorization of the ether extract was effected by pouring the same through a bed of decolorizing carbon supported on a filter aid. Evaporation of the ether from the extract left 6.0 g. of white solid. This solid was purified by dissolving it in hot 2-propanol and allowing it to crystallize therefrom. This procedure was repeated two times more. The purified crystals were identified as 1-phenyl-1-desoxy-D-glucose tetraacetate or 1-phenyl-1-desoxy-2,3,4,6-tetraacetyl-D-glucose. The melting point thereof was 156.5° C. and $(\alpha)_D^{25}$ in chloroform was -16.4° (conc. 0.855 g./100 ml. of chloroform).

Oxidation of the tetraacetate of 1-phenyl-1-desoxy-D-glucose with potassium permanganate produced benzoic acid. The tetraacetate exhibited no reducing power when tested with Fehling's solution.

Deacetylation of 1-phenyl-1-desoxy-D-glucose tetraacetate was effected by dissolving 0.3 g. thereof in 60 ml. of methanol and adding thereto a small piece of sodium. The mixture was permitted to stand for 3 hours. Then the alcohol was removed by evaporation on a hot water bath. There remained 0.2 g. of white powder, 1-phenyl-1-desoxy-D-glucose.

Example 2.—Preparation of 1,1-diphenyl-1-desoxy-2,3,4,5,6-pentaacetyl-D-glucitol. A mixture consisting of 118 g. (0.311 mole) of 2,3,4,6-tetraacetyl-D-glucosyl chloride, 1800 ml. (20.3 moles) of dry benzene, and 347 g. (2.61 moles) of anhydrous aluminum chloride was heated on a steam bath under conditions of refluxing and stirring for 2 hours. Then 20 g. more of aluminum chloride was added and the mixture was stirred and heated for 4 more hours, and then was left over night to cool. The hydrogen chloride which escaped was absorbed in water after being conducted through the reflux condenser and a calcium chloride tube. As the reaction progressed the color of the solution became dark red, and the aluminum chloride layer changed from its powdery form first to a light gum, and finally to a dark sirup.

The contents of the reaction vessel were poured into about 3 liters of cold water to decompose the aluminum chloride complex. The water and benzene layers which formed thereupon were separated. The benzene layer was washed with 10% sodium hydroxide solution, then with water, then dried over sodium sulfate, and distilled. In addition to the excess benzene recovered, there was collected 115.1 g. of acetophenone. Anthracene was isolated from the higher boiling residues.

To the water layer was added the hydroxide washings mentioned above. Then the pH value of said layer was adjusted to approximately 7.0 by means of sodium hydroxide. The large bulk of aluminum hydroxide resulting was removed by filtration through a filter aid, the filter cake being washed repeatedly with water. The clear filtrate obtained was concentrated on a steam bath under diminished pressure until a solid residue, chiefly sodium chloride, appeared. This was extracted several times with pyridine. The pyridine was removed from the extract by distillation under diminished pressure. There was obtained 37–38 g. of a residue from which separated some crystals of 1,1-diphenyl-1-desoxy-D-glucitol, M. P. 155–157° C.

The above mass was acetylated by adding thereto 240 ml. of acetic anhydride and 13 g. of

sodium acetate and heating for two hours at 100° C. The mixture was poured into about 1500 ml. of water and allowed to stand for 10 hours. On extraction of the mixture with ether, followed by evaporation of ether from the extract, 31.6 g. of a thick, amber syrup was obtained. This was dissolved in hot 2-propanol. Upon cooling, 23.5 g. of 1,1-diphenyl-1-desoxy-D-glucitol pentaacetate of 1,1-diphenyl-1-desoxy-2,3,4,5,6-pentaacetyl-D-glucitol, M. P. 90-95° C., separated and was recovered from the alcohol. After repurification in 2-propanol the melting point of the pentaacetate was 95-95.5° C.

Oxidation of 1,1-diphenyl-1-desoxy-D-glucitol pentaacetate with alkaline permanganate produced benzophenone.

Example 3.—Deacetylation of 1,1-diphenyl-1-desoxy-D-glucitol pentaacetate. The pentaacetate (31.7 g.) obtained according to the process described in Example 2 was dissolved in methanol (400 ml.) at 25° C., and freshly cut sodium (about 0.2 g.) was added. After the mixture was allowed to stand for 45 minutes the flask in which the same was contained became filled with small white crystals. After 2 hours these were filtered. They were washed by suspending them in methanol (150 ml.) and refiltering. The yield was 18.4 g. of fine, white needles. Concentration of the mother liquid yielded 1.7 g. more of the crystals. The two crops of crystals were combined and recrystallized from boiling water (2000 ml.). The melting point of the purified product was found to be 157.5-158° C., with preliminary crumpling to a powder at 140-150° C. The compound was identified by suitable analysis as 1,1-diphenyl-1-desoxyglucitol hydrate. Oxidation of the compound by means of alkaline permanganate produced benzophenone.

Example 4.—Preparation of triacetyl-beta-D-xylopyranosylbenzene and 1,1-diphenyl-1-desoxy-D-xylitol. A mixture of 1,2,3,4-tetraacetyl-D-xylene (20 g.; 0.063 mole), dry benzene (300 ml.; 3.39 moles) and anhydrous aluminum chloride (30 g.) was heated under reflux, as in Example 1, for 2½ hours. In this example, however, all of the catalyst was added at the beginning. Acetylation of the syrup obtained from the water layer (after pyridine treatment) yielded 0.82 g. of a light, amber syrup. This was dissolved in hot 2-propanol and the solution permitted to cool. There was obtained 0.17 g. of white needles. M. P. 166-167° C. After recrystallization from 2-propanol the melting point of the crystals was raised to 169.5° C. Another recrystallization failed to raise the melting point. The above compound was identified as triacetyl-beta-D-xylopyranosylbenzene. $(\alpha)_D^{25}$ in chloroform was found to be -57.7° (conc. 0.390 g./100 ml. of chloroform).

Oxidation of the triacetylxylopyranosylbenzene with alkaline permanganate produced benzoic acid.

The solvent was removed from the mother liquor remaining after separation of the triacetylxylopyranosylbenzene. The residue (0.65 g. of syrup) was deacetylated by adding thereto 25 ml. of methanol and a small chip of sodium, and permitting the mixture to stand 2 hours. Removal of the methanol in vacuo left 0.43 g. of a yellow syrup. This was dissolved in hot water, concentrated in an air stream until solidification began, redissolved in water and the solution clarified by passing it through a decolorizing carbon supported on a filter aid. Further concentration of the solution resulted in about 0.1 g. of fine, white needles. These were identified as 1,1-diphenyl-1-

desoxy-D-xylitol. After recrystallization from water the crystals melted at 167-168° C.

Oxidation of 1,1-diphenyl-1-desoxy-D-xylitol with alkaline permanganate produced benzophenone.

Example 5.—Preparation of 1,1-diphenyl-1-desoxy-D-glucitol pentaacetate. Beta-D-glucose pentaacetate (20 g.; 0.05 mole); dry benzene (300 ml.; 3.39 moles); and 95% anhydrous aluminum chloride (45 g.; 0.337 mole) were treated according to the method described in Example 1 except all of the catalyst was added at the beginning. The reflux period was 5 hours, 30 minutes.

From the benzene layer was obtained 11.4 g. of acetophenone and 9.6 g. of residual tars.

From the water layer, after pyridine extraction, was obtained 4.38 g. of an amber syrup. This was fractionally crystallized from 2-propanol. There was obtained 0.4 g. of 1,1-diphenyl-1-desoxy-D-glucitol pentaacetate and 0.30 g. of tetraacetyl-1-phenyl-1-desoxy-D-glucose.

Example 6.—Preparation of 1,1-di-p-tolyl-1-desoxy-D-glucitol. Tetraacetyl-D-glucosyl chloride (20 g.; 0.054 mole); dry toluene (362 ml.; 3.4 moles); and anhydrous aluminum chloride (45 g.) were treated in accordance with the method described in previous examples. The heating period was 5 hours at 75-80° C.

From the toluene layer was obtained 20 ml. of methyl p-tolyl ketone and 20 ml. of pungent, black tar.

From the water layer, after extraction with pyridine, was obtained 4.0 g. of syrup. This was acetylated and yielded 3.24 g. of an amber syrup which set to a hard glass. Deacetylation of 2 g. of this syrup yielded 1.43 g. of an amber syrup which was recrystallized from hot water. The product was identified by suitable analysis as 1,1-di-p-tolyl-1-desoxy-D-glucitol hydrate. After two recrystallizations of the product from water, the melting point of the product was found to be 158.5-160.5° C.

Oxidation of the product with alkaline permanganate yielded 4,4'-benzophenonedicarboxylic acid.

Example 7.—Preparation of 1,1-diphenyl-1-desoxy-D-galactitol and tetraacetylgalactopyranosylbenzene. Beta-D-galactose pentaacetate (20 g.); benzene (300 ml.) and anhydrous aluminum chloride (45 g.) were treated in accordance with the procedure of previous examples. The yield of acetophenone was 8.7 g. The yield of acetylated syrup was 3.7 g. This syrup was deacetylated and the resulting mixture evaporated to dryness. The residue remaining was crystallized from hot water. 1.75 g. of crystals were obtained. These were identified as 1,1-diphenyl-1-desoxy-D-galactitol. After two further crystallizations of the compound from water the melting point of the compound was found to be 175° C. Oxidation of the compound with alkaline permanganate produced benzophenone.

The mother liquor remaining after removal of the 1,1-diphenyl-1-desoxy-D-galactitol crystals described above was evaporated to dryness leaving 0.97 g. of amber syrup. This syrup was re-acetylated. There was obtained 1.24 g. of a clear, amber syrup. This was identified as tetraacetyl-D-galactopyranosyl-benzene.

No claim is made herein to either aryldesoxyglycoses nor to diaryldesoxyalditols as compounds as they are claimed respectively in co-pending applications Serial No. 638,584, filed December 31, 1945, issued as Patent No. 2,460,803, Feb. 8, 1949, and Serial No. 638,585, filed December 31, 1945.

We claim:

1. The process which comprises effecting the reaction, under substantially anhydrous conditions, between tetraacetylglucosyl chloride and benzene in the presence of about 5 molecular equivalents of anhydrous aluminum chloride, based upon the weight of the tetraacetylglucosyl chloride; said reaction being effected at elevated temperature, not exceeding about 100° C. and the time for effecting said reaction being about 7 hours.

2. The process which comprises effecting the reaction, under substantially anhydrous conditions, between tetraacetylglucosyl chloride and toluene in the presence of about 5 molecular equivalents of anhydrous aluminum chloride, based upon the weight of the tetraacetylglucosyl chloride; said reaction being effected at about 75°-85° C. and the time for effecting the reaction being about 5 hours.

3. The process which comprises effecting the reaction, under substantially anhydrous conditions, between 1,2,3,4-tetraacetyl-D-xylose and benzene in the presence of about 4 molecular equivalents of anhydrous aluminum chloride, based upon the weight of the 1,2,3,4-tetraacetyl-D-xylose; said reaction being effected at elevated temperature, not exceeding about 100° C. and the time for effecting said reaction ranging from about 4 to about 8 hours.

4. The process which comprises contacting, under substantially anhydrous conditions and at elevated temperature, not exceeding 100° C., a glucose derivative and an aromatic hydrocarbon in the presence of anhydrous aluminum chloride, said glucose derivative being characterized in that there is attached to the carbon atom of the aldehydic function a substituent selected from the group consisting of Cl, Br and acyloxy and in that the glucose derivative has protected hydroxyl groups; said aluminum chloride being present in the amount of at least about 5 molecular equivalents, based upon the weight of said glucose derivative.

5. The process which comprises contacting, under substantially anhydrous conditions and at elevated temperature, not exceeding 100° C., a glucose derivative and an aromatic hydrocarbon in the presence of anhydrous aluminum chloride, said glucose derivative being characterized in that there is attached to the carbon atom of the alde-

hydic function a substituent selected from the group consisting of Cl, Br and acyloxy and in that glucose derivative has protected hydroxyl groups; said aluminum chloride being present in the amount of about 8 to 10 molecular equivalents, based upon the weight of said glucose derivative.

6. The process of preparing aryldesoxyglycoses and diaryldesoxyalditols which comprises contacting under substantially anhydrous conditions and at elevated temperature not exceeding 100° C. a glucose derivative and an aromatic hydrocarbon in the presence of anhydrous aluminum chloride, said glucose derivative being characterized in that there is attached to the carbon atom of the aldehydic function a substituent selected from the group consisting of chlorine, bromine and acyloxy, and in that the glucose derivative has protected hydroxyl groups; said aluminum chloride being present in the amount of at least about $x-1$ molecular equivalents, based upon the weight of said glucose derivative, where x equals the number of substituents on the carbon atoms of said glucose derivative other than the carbon atom of said function.

7. The process of preparing aryldesoxyglycoses and diaryldesoxyalditols which comprises contacting under substantially anhydrous conditions and at elevated temperature not exceeding 100° C. a glucose derivative and an aromatic hydrocarbon in the presence of anhydrous aluminum chloride and selectively recovering aryldesoxyglycoses and diaryldesoxyalditols, said glucose derivative being characterized in that there is attached to the carbon atom of the aldehydic function a substituent selected from the group consisting of chlorine, bromine and acyloxy, and in that the glucose derivative contains protected hydroxyl groups; said aluminum chloride being present in the amount of at least about $x-1$ molecular equivalents, based upon the weight of said glucose derivative, where x equals the number of substituents on the carbon atoms of said glucose derivative other than the carbon atom of said function.

8. The process according to claim 6 wherein the time of contact ranges from about 4 to about 8 hours.
